APPARATUS FOR ELECTROSTATICALLY TREATING EXTRUDED POLYETHYLENE FILM AND THE LIKE

Iver L. Nelson, Minneapolis, Minn., assignor to Waldorf Paper Products Company, St. Paul, Minn., a corporation of Minnesota

Filed Feb. 21, 1962, Ser. No. 174,846

6 Claims. (Cl. 317—262)

This invention relates to an improvement in method and apparatus for treating extruded polyethylene film and the like, and deals particularly with the use of a dielectric blanket which may be used in the treatment of the film with high frequency current.

Various means have been employed for treating the surface of extruded polyethylene film to produce a surface which may be more readily printed and glued. In some instances, a coating is applied to the surface for the accomplishing of this purpose. In other instances, the surface of the film is oxidized by directing a high frequency current toward the surface, the oxidation of the surface improving its printability and also its receptivity to adhesives. In most instances, this is accomplished by supporting an electrically conductive treating bar in close proximity to the surface of the film, and applying the high frequency current to this treating bar and to the roller over which the film is conveyed. In order to prevent the static electricity from passing through the film and causing pin holes therein, the roller is preferably covered with a dielectric surface which may be glass or certain plastic which overlies the roll and prevents the arcing of the current through the film.

One of the difficulties encountered in this process lies in the fact that considerable time is required to change such dielectric rollers in the event the roller becomes damaged so that the electricity may arc through the film. Furthermore, rollers of this type are usually quite expensive to produce. One of the difficulties involved lies in the fact that there is considerable time and money involved in starting up an extruder and when the dielectric roller is defective, it is normally necessary to completely shut down the extruder for several hours until the roller can be replaced. It has been attempted to pass the film over a fixed dielectric surface. However, this has been found generally practical as the fixed dielectric surface is readily injured by the high frequency current continuously directed toward the same fixed surface.

An object of the present invention resides in the provision of a dielectric comprising a flexible blanket of plastic material which is positioned to overlie a roller over which the treated film is directed. Means are provided for oscillating this blanket back and forth over the roller so as to continually provide a different portion of the blanket between the treating rod and the roller. The blanket is provided with means to simplify the attachment to the apparatus so that in the event the blanket becomes damaged, it may be changed in a very short period of time. As a result, the extruder may merely be moved out of alignment with the apparatus for the time necessary to remove one blanket and to attach another and little time and only a small amount of film forming material is lost.

A feature of the present invention resides in the provision which is attached to the apparatus adjacent to the roller over which the film is to be directed and to provide means for oscillating this frame during operation of the apparatus. The dielectric blanket is attached at opposite ends to opposite sides of the frame, and upon oscillation of the frame, the blanket is drawn first in one direction and then the other to continuously change the portion of the surface of the blanket which is between the treating bar and the roller.

2

These and other objects and novel features of the present invention will be more clearly and fully set forth in the following specification and claims.

In the drawings forming a part of the specification;

5 FIGURE 1 is a side elevational view of a portion of a film extruding apparatus, showing the arrangement of the treating apparatus.

FIGURE 2 is a perspective detail of the treating unit.

FIGURE 3 is a plan view of the blanket in flat form.

10 FIGURE 4 is a perspective detail showing the manner in which one edge of the blanket is secured to the frame.

FIGURE 5 is a perspective detail showing the manner in which the second edge of the blanket is secured to the frame.

15 FIGURE 6 is a sectional view through a portion of the treating bar and roller, and showing the dielectric blanket between the film and the surface of the roller or drum over which the blanket oscillates.

FIGURE 1 discloses a portion of the outlet end of an 20 extruder A which is, in the arrangement illustrated, designed to extrude a film of polyethylene or other suitable such coating to a web of paperboard. The extruder is not illustrated in detail, as such devices are well known in the art. A portion of the extruder frame 10 is designed to support the cooling drum 11, and in the arrangement 25 illustrated, the plastic film is extruded between the web of paperboard and the polished surface of the drum 11, the coated web being indicated at 12 with the surface of the film leaving the smooth surface of the roll 11. The web passes over a pair of idle rollers 13 and 14 and is then directed downwardly around the guide rollers 15 and 16, which in the particular arrangement illustrated, are supported near the floor so that the platform or catwalk 17 may extend across the frame above the film.

30 35 In the particular arrangement illustrated, the frame 10 is separated into the main section 10 which is identified by that numeral, and a winding frame section 19 which supports the rewinding apparatus, not illustrated in the drawings.

40 45 An auxiliary frame portion 20 is interposed between the frame sections 10 and 19 and includes an upright standard 21 which supports a treating roll or drum 22. The web 12 extends upwardly over the treating drum 22 and then around idle rollers 23 and 24 which are also supported at a low elevation so that a second platform or catwalk 25 may extend across the frame.

As is perhaps best illustrated in FIGURE 2 of the drawings, a generally rectangular frame is supported beneath the treating roller 22. The frame 26 includes a 50 pair of parallel end members 27 and 29 which are connected by a pair of parallel angle members 30 and 31. A supporting shaft 32 extends centrally through the end members 27 and 29 in parallel relation to the angles 30 and 31. The shaft 32 is supported by suitable bearings such as 33 which are mounted upon the standards 21 of the auxiliary frame 20. The angle members 30 and 31 are provided with coplanar outwardly directed flanges 34 and 35 respectively through which the dielectric blanket B is anchored.

60 The dielectric blanket B may be formed of a single layer of dielectric material; but in the particular arrangement illustrated, the blanket is formed of a series of laminations of a material commercially known as Mylar which are connected together along opposite ends.

65 As indicated in FIGURE 3 of the drawings, the blanket B is provided with a first series of grommets 37 along one edge thereof, and a second similar series of grommets 39 along the opposite edge of the blanket. The blankets B are made up in advance so that in the event one dielectric blanket is injured, another similar blanket 70 can be substituted in a relatively short period of time.

As is indicated in FIGURE 4 of the drawings, the

outwardly extending flange 35 of the angle frame member 31 is provided with a series of spaced eyebolts 40 which are anchored to the flange 35 by any suitable means such as by the nuts 41. Generally S-shaped hooks 42 connect the spaced eyebolts 40 with the correspondingly spaced grommets 37 along one edge of the blanket to anchor the blanket to one side 31 of the frame. As is indicated in FIGURE 5 of the drawings, the flange 34 of the other frame side 30 is provided with a second series of similar spaced eyebolts 43 which are anchored to the flange 34 by nuts 44 or other suitable means. Tension springs 45 are provided at one end with hook ends 46 designed to extend through an eyebolt 43 and at its other end a hook shaped member 47 designed to extend through a corresponding grommet 39 in the blanket B. In attaching the blanket, one edge of the blanket is connected to the frame side 31 by the hooks 42 and the other end is then attached to the side 30 by the springs 45, the blanket being drawn taut about the periphery of the treating drum 22.

An elongated block 49 of insulating material is suspended above the roll 22 by any suitable means such as that illustrated in FIGURES 2 and 6 of the drawings. The block 49 is provided with a pair of upwardly extending ears 50 through which a suspension rod 51 extends. The rod 51 is supported between suitable sockets 52 in the frame standards 21. The block 49 is provided with a groove 53 extending throughout its lower surface and designed to accommodate the conductive heating bar or rod 54. The rod 54 is anchored in the groove 53 by any suitable means such as by studs 55 which are secured thereto and which extend through apertures in the block 49 and held in place by nuts 56.

The coated web includes a base sheet 57 of paperboard or similar material, and a coated layer 59 of polyethylene or other suitable film. As is evident from FIGURE 6 of the drawings, the blanket B underlies the base sheet 57 and the application of high frequency current between the metal drum 22 and the treating bar 54 produces a discharge from the surface of the bar 54 which oxidizes the surface of the film 59. The current is prevented from arcing through the coated sheet by the dielectric blanket 12.

Suitable means are provided for oscillating or rocking the frame 26 about its supporting shaft 32. In the particular arrangement illustrated, the motor 60 drives a gear reduction 61 which rotates a crank disk 62. A connecting rod 63 is eccentrically pivoted to the disk 62 at 64 and has its other end pivoted at 65 to an arm 66 mounted upon the frame shaft 32. Upon rotation of the disk 62, the arm 66 is oscillated between fixed limits, thus rocking the frame 26 first in one direction and then another.

The drum 22 is normally rotated first in one direction and then in the other by its engagement with the blanket B. The web 12 slips over the surface of the smooth blanket B and is drawn between the treating bar 54 and the drum 22. The corona which is given off by the high frequency treating bar 54 tends to oxidize the surface of the film 59 as it passes beneath this bar.

The process of treating the film in general is similar to that described in an article by J. C. Van Der Heide and H. L. Wilson printed in the May 1961 issue of "Modern Plastics." An alternating voltage generator 70 is connected by a conductor 71 to the treating bar 54 (through the supporting bolts 55), and by a conductor 72 including a suitable resistance 73 to ground at 74 and

to the metal roller 22 which is normally grounded. The electrode 54 produces a corona discharge between the electrode and the dielectric blanket B, or the polyethylene film traveling over the blanket B. The dielectric blanket prevents the current from arcing through pin holes in the film which would act to enlarge these pin holes.

In accordance with the patent statutes, I have described the principles of construction and operation of my improvement in apparatus for electrostatically treating extruded polyethylene film and the like, and while I have endeavored to set forth the best embodiment thereof, I desire to have it understood that changes may be made within the scope of the following claims without departing from the spirit of my invention.

I claim:

1. An apparatus for treating an extruded thermoplastic film the apparatus including a metal roller, a blanket of dielectric material partially wrapped about said roller, means for moving said blanket tangentially of said roller

20 first in one direction and then in the other, means for directing the film to be treated over the roller and dielectric blanket, an electrode supported parallel to, and slightly spaced from, the portion of the sheet over which the film is directed, and a current generator connected between said electrode and said roller for creating a corona discharge between the electrode and the dielectric blanket.

2. The apparatus of claim 1 and in which the means 30 for moving the blanket includes a pivotally supported frame to which the ends of the blanket are secured.

3. The structure of claim 1 and in which the means 35 for moving the blanket includes a generally rectangular frame, and means intermediate the sides of said frame for pivotally supporting said frame, and means securing said blanket to opposite sides of said frame.

4. The structure of claim 1 and in which the means 40 for moving the blanket comprises a member having parallel sides, means supporting said member for pivotal movement on an axis midway between said sides, means for connecting opposite ends of said blanket to said sides, and means for rocking said member about said axis.

45 5. In combination with an apparatus for extruding polyethylene film including a series of rollers over which said film is drawn and a film surface treating device including an electrode supported in spaced relation to the film surface and a current generator connected between 50 a conductive roller and said electrode, a dielectric blanket between said film and said conductive roller, and means for moving said blanket over said surface first in one direction and then the other.

60 6. The structure of claim 5 and in which the means 55 for moving the blanket comprises a frame pivotally supported on an axis parallel to said conductive roller axis, and means securing the ends of said blanket to said frame on opposite sides of the pivot axis, and means for rocking said frame about said pivot axis.
